his wife.

UNITED STATES PATENT OFFICE.

FRED MATHEWS, OF CHICAGO, ILLINOIS, ASSIGNOR TO CLINTON C. MURPHY, OF CHICAGO, ILLINOIS.

CARLINE.

1,230,747.

Specification of Letters Patent. Patented June 19, 1917.

Application filed October 14, 1916. Serial No. 125,712.

To all whom it may concern:

Be it known that I, FRED MATHEWS, a citizen of the United States, and a resident of the city of Chicago, in the county of Cook and State of Illinois, have invented a new and useful Improvement in Carlines, of which the following is a specification.

This invention relates to truss carlines such as are used for freight cars having pitch roofs; and the object of the invention is to produce a light, strong carline from light commercial rolled shapes, such as angle bars and channels.

The invention consists in forming two similarly shaped truss members by kinking up the middle and one-half of two metal angles or channels, arranging them alongside of each other with their kinked-up middle portions crossing and their kinked-up ends oppositely disposed, and riveting them together at the middle and at both ends.

The invention further consists in the details of construction of the carlines shown in the accompanying drawings.

Further objects and details of the invention appear in connection with the following description of the two carlines shown in the drawings; and what the invention consists in is further defined in the appended claims.

In the drawings, wherein the same reference characters designate the same parts in the several views,

Figure 1 is a top plan view of a carline embodying the invention, showing it secured to the side plates of a car;

Fig. 2 is a side view of the same, the side plates being shown in cross-section;

Fig. 3 is a plan view similar to Fig. 1 showing another carline embodying the invention; and

Fig. 4 is a side view of the carline shown in Fig. 3.

The carline shown in Figs. 1 and 2 consists of two angle bars 11, similarly bent up at the middle to form unsymmetrical complementary sections, each of which has a straight horizontal end 12 and a straight inclined end 13. The horizontal ends are oppositely arranged to form the lower chord of the truss, and the inclined ends are oppositely arranged over the horizontal ends to form the ridge and downwardly sloping ends of the top chord of the truss,

when the two sections are secured together. The sections 11 are arranged with their vertical flanges in contact at the ends and their horizontal flanges up and projecting away from each other. The middle portions of the sections are riveted one on each side of a plate 14, the upper edge is bent over to form a horizontal flange 15 upon which the ridge pole of the car may be supported and held by a vertical bolt. The ends 16 of the horizontal flanges are bent down inside of the side plates 17; and gusset plates 18 are riveted to the tops of the horizontal flanges and bent over the side plates. The ends of the gusset plates and the downwardly bent ends of the carline flanges are bolted together through the side plates and secure the carlines to the side plates.

In the carline shown in Figs. 3 and 4, the sections 19 are formed from angle bars bent up at the middle and on one side, as in the carline described above. The middle bends of the angle bars in the carline shown in Figs. 3 and 4 are sharper than in the carline shown in Figs. 1 and 2; and the middle sections of the angle bars contact with each other and are riveted together to form a vertical middle strut 20. The ends of the carline are flanged down and provided with supporting plates 17, like those of the carline shown in Figs. 1 and 2.

The invention is not restricted to the shapes and forms of metal bars shown in the drawings.

What I claim as my invention is the following:

1. A carline comprising two similarly shaped structural metal members, said members being disposed in vertical planes side by side with their middle portions crossing each other and diverging and their end portions converging, said members being connected at the middle and ends to form a truss.

2. A carline comprising two similarly shaped structural metal members, said members being disposed in vertical planes side by side with their middle portions crossing each other and diverging and their end portions converging, said members being connected at the middle and ends to form a truss, and a connecting plate secured between the crossing middle portions.

3. A carline of truss form comprising

two complementary members having vertically disposed flanges and secured together at the middle, the ends of said members being bent in opposite directions and adjacent ends converging toward the ends of the carline, where the vertical flanges are secured together.

4. A carline of truss form comprising two complementary members having vertically disposed flanges and secured together

at the middle, the ends of said members being bent in opposite directions and adjacent ends converging toward the ends of the carline, and gusset plates riveted to the ends of said members to secure them together 15 and support the carline upon the side plates of a car.

Signed at Chicago, Ill., this 10th day of October, 1916.

FRED MATHEWS.
